UNITED STATES PATENT OFFICE.

HENRY H. CUTLER, OF CHICAGO, ILLINOIS.

CONTROLLER FOR ELECTRIC VEHICLES.

SPECIFICATION forming part of Letters Patent No. 697,987, dated April 22, 1902.

Application filed August 24, 1899. Serial No. 728,266. (No model.)

To all whom it may concern:

Be it known that I, HENRY H. CUTLER, a citizen of the United States, residing at Chicago, in the county of Cook and State of Illinois, have invented a certain new and useful Improvement in Controllers for Electric Vehicles, of which the following is a full, clear, concise, and exact description, reference being had to the accompanying drawings, forming a part of this specification.

My invention relates to a controller for electric vehicles, my object being to provide effective means for directing the current through the motor or motors employed for operating the vehicle.

In accordance with the present invention I provide a plurality of solenoids or magnets for controlling the circuits through the several elements of the power-supply—as, for instance, the fields and armatures of the electric motors used for driving the vehicle. It has been the usual practice heretofore to provide a controller-roller or other form of switching mechanism, the contacts of which directly control the circuit through the several elements. As these contacts are often required to carry currents of considerable volume, excessive arcing takes place at the contacts of the controller-roller, thereby decreasing the effectiveness of the operation of the roller or necessitating the employment of a very large controller-roller in order to provide sufficiently large contacts. In accordance with my invention I arrange the controller-roller or other switching mechanism to control the circuits through the solenoids, and the solenoids control the circuits through the elements of the power-supply. In this manner the contacts which carry the heavy operating-currents are controlled by the solenoids, and as the solenoids can be placed beneath the car or in any other convenient place the contacts may be made of sufficient size to carry the necessary large currents employed.

While I have illustrated my invention in connection with a controller for electric vehicles such as are usually employed in street-railway systems, it is obvious that my invention may be applied to other forms of vehicles, as elevators, cranes, and the like, and that it can be employed generally for the control of electric motors used for supplying power to

any desired mechanism. It will also appear that my invention is not limited to the control of circuits through the fields and armatures of electric motors, but is equally applicable to the control of circuits through the several elements of any source of power-supply.

I have illustrated my invention in the accompanying drawings, in which—

Figure 1 is a diagram illustrating the circuit connections of a controller for an electric vehicle equipped in accordance with my invention. Fig. 2 is a plan view of the operating mechanism of the controller-roller. Fig. 65 3 is a view thereof in elevation, partially in section. Fig. 4 is a diagram illustrating a modification of my invention. Fig. 5 is a plan view of a modified form of controller-roller. Fig. 6 is a view thereof in elevation. Fig. 7 70 is a view illustrating the circuits upon several vehicles connected together to form a train.

Like letters refer to like parts in the several figures.

Referring to Fig. 1, I have illustrated a pair 75 of electric motors the elements of which are adapted to be connected in series and in parallel relation to secure the varying speeds at which the vehicle is to be driven.

While I have employed throughout the 80 drawings a series-parallel system for the purpose of illustrating my invention, it will be understood that the invention is equally applicable to any other method of employing the electric motor or motors.

The controller-rollers *i* and *i'* are provided, respectively, at the front and rear of the vehicle, and each comprises a plate of metal or other conducting material wrapped about a suitable support to form a roller, and in Fig. 90 1 the plates are illustrated as developed or rolled out into a plane for better illustration. The rollers are provided upon the surfaces with raised portions at intervals to constitute the contact-surfaces, these portions being indicated by the shaded parts of the rollers shown in the drawings. Brushes *a* to *g*, inclusive, are connected, respectively, with the ends of the solenoids *A* to *G*, respectively, the several solenoids being provided with main 100 windings *A'* to *G'*, respectively, and auxiliary windings *A''* to *G''*, respectively, one end of the main winding being connected with the trolley-wire, as is also the end of the auxiliary

- winding. The cores A³ to G³, respectively, of the solenoids each carry at the lower end a contact-plate a², normally bridging together contacts a³ a⁴, thereby short-circuiting the auxiliary winding of the solenoids. When the solenoid is energized and the core is raised, the contact-plate a² is moved out of engagement with the contacts a³ a⁴, and the short circuit around the auxiliary winding is thus opened, thereby including the auxiliary winding in circuit with the main winding of the solenoid. A brush a' is provided in connection with each of the controller-rollers, which is connected by means of a conductor 10 with the rail or return circuit of the system.
- The starting resistance n of the motors is connected at one end to the trolley-conductor and with a conductor 1, which extends to the contact 1^a, provided in connection with solenoid A. The opposite end of resistance n is connected by conductor 2 with contact 2^a of solenoid A and contact 2^b of solenoid C. The field-winding p' of one of the motors is connected at one end to the starting resistance and at the other end to a conductor 3, which extends to contact 3^a of solenoid B and contact 3^b of solenoid C. Field-winding m' of the other motor is connected at one end with conductor 4, which extends to contact 4^a of solenoid B and contact 4^b of solenoid C, while the opposite end of said winding is connected by conductor 5 with contact 5^a of solenoid C, contact 5^b of solenoid F, and contact 5^c of solenoid G. The armature p of the first motor is connected with conductor 6, extending to contact 6^a of solenoid E, contact 6^b of solenoid F, and contact 6^c of solenoid G. The opposite side of the armature is connected by conductor 7 with contact 7^a of solenoid D and contact 7^b of solenoid E. One end of armature m is connected by conductor 8 with contact 8^a of solenoid D and contact 8^b of solenoid E, while the other end of the armature is connected with conductor 9, which extends to contact 9^a of solenoid E, contact 9^b of solenoid F, and contact 9^c of solenoid G. The rail or return conductor is connected with conductor 10, which extends to contact 10^a of solenoid A, contact 10^b of solenoid F, and contact 10^c of solenoid G.
- The overload-solenoid O has a coarse winding o³, which is connected in series with the working circuit through the motors and has a fine winding o², which is connected to the trolley-wire and contact o' of solenoid A. The end of solenoid A is connected directly with the trolley-wire, while the ends of the remaining solenoids are connected by conductor 20 through contacts o⁴ o⁵ o⁶, controlled by the overload-magnet O, the contact o⁵ being carried upon the core of the solenoid and being moved out of engagement with the contacts o⁴ o⁶ when the solenoid or magnet is energized, thereby opening the circuit through the solenoids B to G. The solenoids carry contact-plates, which serve to bridge together the pairs of contacts when the solenoids are energized to thereby elevate the cores. The cores of solenoids B and C are connected together by means of an arm b', pivoted at b², whereby when one of the cores is elevated the other will be depressed. The cores of solenoids D and E are likewise connected together, as are also the cores of solenoids F and G.
- The following table gives the connections made by the several solenoids when energized, the numerals indicating the conductors, which are electrically united when the solenoids are energized:
Table of Connections Made by Solenoids. A connects 1 with 2 and fine-winding solenoid O. B connects 3 with 4. C connects 2 with 4 and 3 with 5. D connects 7 with 8. E connects 6 with 8 and 7 with 9. F connects 5 with 6 and 9 with 10. G connects 5 with 9 and 6 with 10.	80 85 90 95 100 105
- By reference to this table it will be noted that A by connecting conductors 1 and 2 short-circuits the starting resistance. The solenoid B when energized connects the motor-fields in series. The solenoid C by uniting conductors 2 and 4 and 3 and 5 connects the motor-fields in parallel. Solenoid D connects the motor-armatures in series. Solenoid E connects the armatures in parallel. Solenoid F connects the fields with the armatures and connects the armatures with the rail. Solenoid G accomplishes the same result as solenoid F, except that the armatures are connected in circuit in reversed direction.
- The following table of the uses of the solenoids will facilitate the reading of the drawings:
Uses of the Solenoids. A short-circuits starting resistance and connects winding o² in circuit. B connects the motor series fields in series. C connects the motor series fields in parallel. D connects the motor-armatures in series. E connects the motor-armatures in parallel. F connects the motor-armatures for forward speeds. G connects the motor-armatures for backward speeds. O opens the motor-circuit when overloaded.	110 115 120 125 130
- Referring to the diagram of the controller i, the horizontal lines indicate the position of the brushes necessary for securing the operation indicated upon the left. Thus in the position 1 1 the vehicle is at rest and the brushes are in the "off" position. In the position 2 2 the brushes are in position for very slow movement, and in this position solenoids F, D, and B are energized, as indicated in the drawings. In the position 3 3 for slow speed the solenoids F, D, B, and A are energized. In the position 4 4 for medium speed the solenoids F, D, C, and A are energized. In the position 5 5 for fast speed the solenoids F, E, C, and A are energized. In the

position 6 6 for back speed the solenoids G, D, and B are energized. The solenoids energized by the operation of the rear controller i^7 are likewise shown at the left of said controller.

5 Supposing the vehicle to be at rest and the brushes in the off position 1 1 and it be desired to move the vehicle forward, the controller is moved to bring the brushes in the position 2 2, in which case the brushes f , d , b , and a' engage the contact-surfaces of the roller i , thereby energizing the solenoids F, B, and D. The armatures and fields of the motors are thus connected in series, with the starting resistance n in circuit. When the brushes are moved to the position 3 3, the solenoid A is energized in addition, and the starting resistance is thus short-circuited. In moving the controller to the position 4 4 the brushes f , d , and b pass out of engagement

10 with the contact-surfaces of the roller, and the solenoids are thus deenergized, permitting the cores to fall. In the position 4 4 the brushes f , d , c , and a are in circuit, thereby energizing the corresponding solenoids, and

15 the fields of the motor are connected in parallel, while the armatures remain in series. In the position 5 5 brushes f , e , c , and a are in circuit, thereby energizing the corresponding solenoids and connecting the armatures

20 of the motors also in parallel. When the brushes are moved to the position 6 6, brushes g , d , and b are connected in circuit, thereby energizing the corresponding solenoids and connecting the motors in series, with the armatures in reversed position, whereby the

25 vehicle is propelled backward. As the solenoids of the pairs B C, D E, and F G perform opposite functions and as both solenoids of the pair should not be energized at one time,

30 the linking of the cores of the solenoids together by the pivoted levers insures the operation of but one solenoid of each pair at a time. When the circuit is closed through any one of the solenoids, the current traverses the main winding thereof, which is of comparatively low resistance, whereby sufficient current flows to attract and raise the core. The upward movement of the core serves to open the short circuit around the

35 auxiliary winding, thereby connecting said winding in circuit and increasing the resistance of the solenoid-winding sufficiently to cut down the current flowing to a strength sufficient to maintain the core in its elevated

40 position. When an abnormal current flows through the motor-circuits, the coarse windings o^5 of the overload-magnet O are energized, thereby raising the contact o^6 as the core is attracted, thus opening the circuit through

45 the solenoids B and G. The fine-wire winding remains in circuit and is traversed by sufficient current to maintain the core of solenoid O in an elevated position. The solenoid A is not in circuit with the contacts o^4 o^5 o^6 ,

50 so that when an abnormal current flows the fine-wire winding remains in circuit.

In Figs. 2 and 3 I have illustrated the pre-

ferred form of mechanical arrangement for the controller-roller, the contact-plate i being mounted upon a drum or roller which is provided with a handle i^2 , adapted to be rotated into the various positions to move the contact-plate relatively to the row of brushes, the different positions of the handle for the various speeds being indicated. A stop i^3 is carried upon a lever i^4 , pivoted at i^5 , the lever being pressed upward by means of a spring i^6 . The stop i^3 extends upward sufficiently to limit the movement of the arm i^2 , so that the arm normally cannot be moved beyond the off position. When it is desired to back the vehicle, the lever i^4 is depressed, thereby lowering the stop i^3 , so that the arm i^2 can be moved past the stop to the "back" position. A permanent stop i^7 limits the further movement of the handle i^2 .

In Fig. 4 I have illustrated a further development of my invention in which, in addition to the solenoids A to G, a solenoid H is provided. In this figure I have illustrated, 90 in addition to the series field-coils $m^1 p^1$, shunt field-coils m^2 and p^2 , these coils being connected together in series and joined at one end to the trolley-wire and at the other end to a conductor 18, which extends to contacts 95 18^b, provided in connection with solenoid B. An additional contact 10^d is provided in connection with solenoid B and is connected with conductor 10. I have illustrated a non-inductive resistance n^2 in parallel with the shunt field-coils $m^2 p^2$ for the purpose of affording a path for the inductive surge when the shunt-coils are removed from circuit. A resistance n' is connected at one end with conductor 6 and at the other end with a conductor 16, which extends to contact 16^a of solenoid H. The contact 9^d of solenoid H is connected with conductor 9. The solenoid H is provided with main and auxiliary coils in like manner as the other solenoids, the short 105 circuit about the auxiliary coil being opened when the solenoid is energized. The end of the solenoid-winding is connected with brushes h h , adapted to engage the contact-plates i and i' when the brushes occupy the position 110 7 7 or the position 8 8. When the brushes are in either of these positions, the said solenoid is energized.

The operation of the system as above described and as illustrated in Fig. 4 is as follows: 120 When the brushes are in the off position 1 1, the circuits are open and the vehicle is at rest. When it is desired to move the vehicle forward, the brushes may be moved to the positions 2 2 3 3, &c., to cause the vehicle to travel at any 125 desired speed, and the circuits closed in the various positions are the same as described in connection with Fig. 1. When solenoid B, however, is energized, the shunt-fields m^2 and p^2 are included in circuit. Thus when 130 the brushes are in the "very-slow" position the solenoid B is energized and the shunt-fields are in circuit, thereby adding the strength of the shunt-fields to that of the se-

ries fields. Likewise in the "slow" position the shunt-fields are in circuit. In the "medium" and "fast" positions the shunt-fields are removed from circuit. When it is desired to stop the vehicle, the dynamic brake is applied by moving the brushes to the position 8 8, in which solenoids H, E, and B are energized. In this position the shunt field-coils are included in circuit, while the series field-coils m' and p' are removed from circuit. The magnetic field is thus due to the shunt-fields alone. In this position the contacts 16^a and 9^d are closed together by the solenoids H, so that the armatures m and p are included in a closed circuit with the resistance N', the armatures being in parallel with each other. The armatures being thus rotated in a magnetic field while closed upon themselves serve as a dynamic brake to check the movement 20 of the vehicle. When the brushes are moved to the "full-stop" position 7 7, the solenoid E is deenergized and the solenoid D is energized, thereby connecting armatures m and p in series with each other instead of parallel, 25 the connections remaining otherwise the same, and an increased dynamic action thus results. In the back position the circuit arrangements are the same as described in connection with Fig. 1, except that the shunt field-coils m^2 and p^2 are included in circuit.

In Figs. 5 and 6 I have illustrated a modified form of the controller in which the handle e , by means of which the drum is rotated, carries a pivoted lever, the arm e^1 of which is in position to be readily grasped by the hand to rock the lever and move the arm e^2 upward and out of the path of the stops e^3 e^4 . The stop e^3 is in position to normally prevent the movement of the handle e beyond the off 40 position. When it is desired to move the handle to stop the vehicle, the closing of the hand upon the handle serves to raise the arm e^2 out of the path of the stop e^3 to permit the movement of the handle e to the full-stop 45 position. When it is desired to back the vehicle, the arm e^2 may be likewise raised to permit the handle e to pass the stop e^4 .

In Fig. 7 I have illustrated diagrammatically a number of cars coupled together in accordance with my invention. A set of solenoids A to K, inclusive, is illustrated upon each car, the solenoids being connected with the contacts of the controllers by means of conductors which extend throughout the length 55 of the train.

By the term "solenoid" as employed in the appended claims I contemplate any form of electromagnetic motive device.

Having described my invention, what I 60 claim as new, and desire to secure by Letters Patent, is—

1. In a controller for electric motors, the combination with the fields and the armatures of a pair of electric motors, of contacts arranged to connect the fields either in series or in parallel relation, contacts ar-

ranged to connect the armatures either in series or in parallel relation independently of said fields, a plurality of solenoids for controlling circuit through the several contacts, 70 and a switching device for actuating the solenoids, substantially as described.

2. In a controller for electric motors, the combination with the fields and the armatures of a pair of electric motors, of resistances associated with the armatures and the fields, contacts for controlling circuit through said resistances, contacts for connecting the fields in series or parallel, contacts for connecting the armatures in series or parallel independently of said fields, a plurality of solenoids for controlling said contacts, and a switching device for connecting the several solenoids in circuit as desired, substantially 80 as described. 85

3. In a controller, the combination with a plurality of contacts, of a plurality of solenoids for controlling circuit therethrough, one end of each solenoid being connected with one side of the supply-circuit, a series of 90 brushes one connected with the opposite end of each solenoid, and a contact-plate connected with the opposite side of the supply-circuit and having raised contact-surfaces arranged to engage the respective brushes to 95 close circuit through the several solenoids, substantially as described.

4. In a controller, the combination with the several elements of the source of power-supply to be connected in varying relations, of 100 contacts connected therewith, a plurality of solenoids for controlling the circuits through the several contacts, said solenoids being provided with main and auxiliary windings, and a shunt-circuit normally provided around the 105 auxiliary winding and adapted to be opened when the core is attracted to thereby connect the auxiliary winding in circuit, substantially as described.

5. In a controller, the combination with the 110 several elements of the source of power-supply to be connected in varying relations, of contacts connected therewith, a plurality of solenoids for controlling the circuits through the several contacts, and an overload-solenoid 115 for controlling the circuits through the solenoids, substantially as described.

6. In a controller, the combination with the several elements to be connected in varying relations, of contacts connected therewith, a 120 plurality of solenoids for controlling the circuits through the several contacts, and an overload-solenoid for controlling the circuits through the solenoids, said overload-solenoid being provided with a series winding and a 125 shunt-winding, and a solenoid for controlling the circuit through said shunt-winding, substantially as described.

7. In a controller for electric motors, the combination with a pair of electric motors, of 130 a solenoid for connecting the fields thereof in parallel, a solenoid for connecting said fields

in series, a switching apparatus for closing circuit through the solenoids, and separate means for varying the circuit connection of the armatures of said motors, substantially 5 as described.

8. In a controller for electric motors, the combination with a pair of electric motors, of a solenoid for connecting the fields thereof in parallel, of a solenoid for connecting said fields 10 in series, a connection between the cores of said solenoids whereby but one of said cores can be attracted at a time, and switching apparatus for closing circuit through the solenoids, substantially as described.

15 9. In a controller for electric motors, the combination with a pair of motors, of a solenoid for connecting the armatures thereof in series, a solenoid for connecting the armatures in parallel, switching apparatus for closing circuit through said solenoids, and separate means for varying the circuit connections of the fields of said motors, substantially as described.

10. In a controller for electric motors, the 25 combination with a pair of motors of a solenoid for connecting the armatures thereof in series, a solenoid for connecting the armatures in parallel, a connection between the cores of said solenoids whereby but one of 30 said cores can be attracted at a time, and switching apparatus for closing circuit through the solenoids, substantially as described.

11. In a controller for electric motors the 35 combination with a pair of electric motors, of a solenoid for connecting the armatures thereof in circuit in one direction, a solenoid for connecting the said armatures in the reversed direction, switching apparatus for closing circuits through the solenoids, and separate 40 means for varying the circuit arrangement of the fields of said motors, substantially as described.

12. In a controller for electric motors, the 45 combination with a pair of electric motors, of a solenoid for connecting the fields thereof in circuit in series, a solenoid for connecting said fields in parallel, switching apparatus for closing circuit through the solenoids, and 50 separate means for varying the circuit ar-

angement of the armatures of said motors, substantially as described.

13. In a controller for electric motors, the combination with a pair of electric motors, of a solenoid for connecting the fields thereof in 55 parallel, a solenoid for connecting the fields thereof in series, a solenoid for connecting the armatures thereof in parallel, a solenoid for connecting the armatures thereof in series, and switching apparatus for closing circuit 60 through the several solenoids, substantially as described.

14. In a controller for electric motors, the combination with a pair of electric motors, of a solenoid for connecting the fields thereof in 65 parallel, a solenoid for connecting the fields thereof in series, a solenoid for connecting the armatures in circuit in one direction, a solenoid for connecting the armatures in circuit in the opposite direction, and switching 70 apparatus for closing circuit through said several solenoids, substantially as described.

15. In a controller for electric motors, the combination with a pair of electric motors, of a solenoid for connecting the armatures thereof in series, a solenoid for connecting said armatures in parallel, a resistance, a solenoid for connecting said resistance in closed circuit with said armature, and switching apparatus for closing circuit through said several 80 solenoids, substantially as described.

16. In a controller for electric motors, the combination with a pair of electric motors having shunt-fields, of a solenoid for controlling the circuit through said shunt-fields, a 85 solenoid for connecting the armatures in series, a solenoid for connecting the armatures in parallel, a resistance, a solenoid for connecting said resistance in a closed circuit with the armature, and switching apparatus 90 for closing circuit through the several solenoids, substantially as described.

In witness whereof I have hereunto subscribed my name in the presence of two witnesses.

HENRY H. CUTLER.
